UNITED STATES PATENT OFFICE.

EDUARD KELLER, OF FREIBURG, GERMANY.

DESIGN FOR AN ELECTRIC TABLE-LAMP ALARM CLOCK.

Application filed December 4, 1928. Serial No. 29,107. Term of patent 14 years.

To all whom it may concern:

Be it known that I, EDUARD KELLER, a citizen of Germany, residing at Freiburg (Breisgau), Germany, and whose post-office address is Lowenstrasse 6, in said city, have invented a new, original, and ornamental Design for an Electric Table-Lamp Alarm Clock, of which the following is a specification, reference being had to the accompanying drawing, forming part thereof.

Fig. 1 is a side view of an electric table-lamp alarm-clock of my new design;

Fig. 2 is another side view thereof, taken at an angle of 90° relative to that shown in Fig. 1.

I claim:

The ornamental design for an electric table-lamp alarm-clock, as shown.

EDUARD KELLER.
